UNITED STATES PATENT OFFICE.

THOMAS E. GAMMON AND HENRY D. AVERILL, OF HAVERHILL, MASSACHUSETTS,
ASSIGNORS OF ONE-HALF TO LINE MATERIAL COMPANY, OF SOUTH MILWAUKEE,
WISCONSIN, A CORPORATION OF WISCONSIN.

TREE INSULATOR.

Application filed November 19, 1924. Serial No. 750,787.

The invention relates to insulators and has for an object to provide an insulator for supporting a line wire out of contact with trees or other obstructions in its path.

5 Another object of the invention is to provide an insulator in which the insulator body may be secured to a base member in more than one position, and is detachable therefrom to afford facility in installation.

10 The invention further consists in the several features hereinafter set forth and more particularly defined by claims at the conclusion hereof.

In the accompanying drawings: Fig. 1 is 15 an elevation of an insulator embodying the invention secured to a support in one of its mounting positions;

Fig. 2 is an elevation of the insulator in another of its mounting positions;

20 Fig. 3 is a side elevation of the insulator in the assembly shown in Fig. 1, parts being broken away and parts being shown in section; and

Fig. 4 is a top view of the insulator.

25 In these drawings 10 indicates an insulator body and 11 a base member to which it is secured.

The insulator body is preferably square in cross section and has spaced projections 30 12 at its head end providing a transversely extending slot 13 between them. The projections are preferably in the form of hooks extending in opposite directions and have their ends spaced from the body of the insulator to form passages 14. A central wire-receiving passage 15 is also formed in the insulator body and extends transversely of the insulator body preferably at right angles to the slot 13 and the hooks 12.

A reduced flat-sided shank 16 extends from the other end of the insulator body, which is preferably peltcoated adjacent the shank to reduce leakage losses, as shown in Fig. 3. Opposite sides of the outer portion of the shank are still further reduced to form shoulders 17, and an opening 18 extends transversely through the shank from the reduced shoulder-forming sides.

The base member 11 has a threaded attaching member 19 cast or otherwise firmly secured in one end to prevent relative rotation. The projecting portion of the attach-

ing member is in the form of a lag screw or bolt, a lag screw being used when attaching the base member to wood and a bolt 55 when attaching it to a metal support.

The other end of the base member is provided with a pair of flat-sided resilient projections 20 forming a fork engaging the shank of the insulator body and having 60 aligned openings 21 to register with the opening 18 for the reception of a bolt 22 receiving a nut 23 for clamping the fork on the shank.

When conditions make it desirable to use 65 the assembly shown in Fig. 1, in which the insulator body and base member are aligned, the flat end edges 24 of the projections 20 abut against the shoulders 17 to prevent swinging of the insulator about the 70 bolt, and in the assembly shown in Fig. 2, in which the insulator body and base member are at right angles, the flat side edges 25 of the projections perform a similar function.

The base member is screwed into a tree or other obstruction from which it is desired to space the line wire 26, the slot 19 of the insulator being preferably parallel with the wire when the assembly of Fig. 1 is used. The wire is then pushed into the slot and the insulator given a quarter turn to bring the wire through the passages 14 into the passage 15 where it is held against removal.

When using the assembly of Fig. 2, the line wire is turned into place on the insulator body, or the insulator body is removed from the base member for placement on the line wire, and is then replaced on the base member, which has been previously screwed into its support by a turning tool engaging it at some convenient place.

The device is particularly useful in guiding a free span of wire through the branches of trees, the insulator being readily secured to the branches to hold the wire out of contact therewith and being attachable before or after the wire has been strung. The insulator body and base member are rigidly held together and may be assembled in either of two positions which makes it possible to provide either vertical or horizontal mounting of the base member while re-

taining the insulator body in the same position, and to vary the spacing of the wire from the support.

While the insulator body is preferably formed of porcelain, it will be understood that it may be of moulded plastic insulating material.

What we claim as new and desire to secure by Letters Patent is:

- 10 1. An insulator for spacing line wires away from adjacent objects comprising a block of insulating material having a wire-engaging head and a reduced integral flat-sided shank provided with shoulders at opposite sides, an attaching member having a threaded projection at one end to enter a support and a parallel-sided fork at the other end engaging opposite sides of said shank, and a retaining member passing through said shank portion and fork for holding said block on said attaching member with portions of said fork abutting against said shoulders to prevent relative movement of said block and attaching member.
- 15 2. An insulator for spacing line wires away from adjacent objects comprising a block of insulating material having spaced projections at one end to hold the wire when the insulator and wire have been turned with respect to each other and provided with a reduced integral shank at the other end affording shoulders, an attaching member having a threaded projection at one end to enter a support and a pair of spaced projections at the other end for engaging opposite sides of said shank, and means for holding said block on said attaching member with portions of said spaced projections
- 20
- 25
- 30
- 35

abutting against said shoulders to prevent movement of said insulator block on said attaching member.

3. An insulator for spacing line wires away from adjacent objects comprising a block of insulating material having a wire retaining portion and an integral flat-sided shank portion with oppositely disposed shoulders, an attaching member having a threaded projection at one end to enter a support and a pair of spaced projections at the other end for engaging opposite sides of said shank portion with edges of said spaced projections abutting against said shoulders, and a retaining member passing through said shank portion and said spaced projections for holding said insulator body to said attaching member.

4. An insulator for spacing line wires away from adjacent objects comprising a block of insulating material having a wire retaining portion and an integral flat-sided shank portion with shoulders on opposite sides thereof, an attaching member having a threaded projection at one end to enter a support and a pair of spaced projections at the other end for engaging the opposite shouldered sides of said shank portion, and a retaining member passing through said shank portion and said spaced projections for holding said insulator body to said attaching member, the edges of said spaced projections cooperating with said shoulders to retain said insulator block on said attaching member in different angular positions.

In testimony whereof, we affix our signatures.

THOMAS E. GAMMON.
HENRY D. AVERILL.
